(57) **CLAIM**

The ornamental design for a charging station for electric vehicles as shown and described.

DESCRIPTION

FIG. 1 is a front, left and bottom perspective view of a charging station for electric vehicles according to a first embodiment of my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an encircled portion 9 of FIG. 1;

FIG. 10 is an enlarged view of an encircled portion 10 of FIG. 1;

FIG. 11 is a front, left and bottom perspective view of a charging station for electric vehicles according to a second embodiment of my new design;

FIG. 12 is a rear, right and top perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof;

FIG. 19 is an enlarged view of an encircled portion 19 of FIG. 11; and,

FIG. 20 is an enlarged view of an encircled portion 20 of FIG. 11.
